(57) **CLAIM**

The ornamental design for a shooting stabilizer with remote control, as shown and described.

DESCRIPTION

FIG. 1 is a perspective view of a remote control of a shooting stabilizer with remote control showing our new design, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a shooting stabilizer of the shooting stabilizer with remote control, shown separately for ease of illustration and shown in a first configuration of use;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the shooting stabilizer where the shooting stabilizer is in a second state;

FIG. 18 is a perspective view of the shooting stabilizer where the shooting stabilizer is in a third state;

FIG. 19 is a perspective view of the shooting stabilizer where the shooting stabilizer is in a fourth state;

(Continued)

FIG. 20 is a perspective view of the shooting stabilizer with remote control where the remote control is received in a groove of the shooting stabilizer;

FIG. 21 is an enlarged view of portion 21 shown in FIG. 10; and,

FIG. 22 is an enlarged view of portion 22 shown in FIG. 12. The dash-dash broken lines in the drawings depict portions of the shooting stabilizer with remote control that form no part of the claimed design. The dash-dot broken lines depict boundaries of the enlarged portions of the shooting stabilizer with remote control that form no part of the claimed design.
